UNITED STATES PATENT OFFICE.

JOHN W. LUNDGREN, OF DULUTH, MINNESOTA.

DRILLING-MACHINE.

974,406.

Specification of Letters Patent.

Patented Nov. 1, 1910.

Application filed April 30, 1908, Serial No. 314,449. Renewed June 18, 1910. Serial No. 507,686.

To all whom it may concern:

Be it known that I, JOHN W. LUNDGREN, a citizen of the United States, residing at Duluth, in the county of St. Louis and State 5 of Minnesota, have invented certain new and useful Improvements in Drilling-Machines; and I do hereby declare the following to be a full, clear, and exact description of the invention, such as will enable others 10 skilled in the art to which it appertains to make and use the same.

My invention relates to drilling machines, and has for its object the provision of means for feeding to the drills the material or articles 15 to be drilled, adjustable means for carrying the drills, whereby the position of the drills may be shifted transversely to the direction of movement of the articles to be drilled, and means for locking said 20 adjustable means in one or another predetermined position with respect to the article to be drilled.

It includes certain other constructions, combinations, and arrangements of parts 25 hereinafter described and claimed.

In the drawings Figure 1, is a perspective view of my said invention, omitting the tables or approaches upon which the article to be drilled comes to, or departs from 30 the main machine. Fig. 2, is a fragmentary central vertical sectional view of the pressure yoke and, partly in elevation, of the vertically movable support for the article to be drilled, and of the lower ends of the 35 drills. Fig. 3, is a fragmentary view, partly in vertical section and partly in elevation, of guide blocks on the head frame, and of the exposed face of the pressure yoke mounted in said guide blocks, and of the lower 40 end of the drill. Fig. 4, is a central transverse vertical sectional view of said invention, omitting the approaches. Fig. 5, is a horizontal sectional view, (on the line A—B of Fig. 4), of that part of my invention 45 which is above the line C—D of Fig. 4. Fig. 6, is a side elevation partly in vertical section and partly broken away, of my said invention. Fig. 7, is an enlarged side elevation of the lever and dog for locking the 50 head frame against transverse movement. Fig. 8, is a section of said lever and dog on the line E—F of Fig. 7. Fig. 9, is a side elevation, partly in section and partly broken away, of my said invention, omitting the 55 approaches. Fig. 10, is an enlarged central

vertical sectional view of one of the drills and of the supports therefor. Fig. 11, is a plan view of a portion of an unfinished match-carrying belt in which my invention is adapted to drill the match or splint-holding holes.

In the drawings, 1 is a main frame, preferably comprising several members having a fixed or stationary relation to each other and adapted to support the movable parts 65 of the machine. Said frame 1 preferably includes brackets 1^a in which is mounted an axle, or hinge pin 1^b, upon which axle is journaled a transversely movable head frame 2, which is adapted in lowered position to rest upon a suitable stop, which may consist of the upper end of the main frame, as at 1^c, and said head frame may be locked in such lowered position by sliding tongues 3, mounted in said main frame and adapted 70 to overlap a portion of said frame 2. The tongues 3 are preferably dovetailed into the frame 1, or vice versa and may be locked against movement by set screws 3^a. Pivotal secured at one end to said frame 2, is 75 a link 4, which at its other end is loosely pivoted to a lever 5, which lever 5 is pivotally secured to, or fulcrumed upon the frame 1, as at 5^a. When the frame 2 is swung upwardly and backwardly, the pivotal relation between the link 4 and the lever 5 is suspended by the separation of those members, but when the frame 2 is lowered again the pivotal relation between the link 4 and lever 5 should be reestablished by 80 the reinsertion of the pivot pin, carried by either member, into the aperture therefor formed in the opposing member. By operating said lever 5, the frame 2 may be drawn in one direction or thrust in the opposite 85 direction transversely of said frame 1 and along said axle 1^b. Pivotal mounted upon said frame 1, is a lever 6 carrying a dog 6^a provided with a tooth or teeth adapted in operation to project into one or another of 90 the indentations formed in a serrated lug 2^a formed on said frame 2, or vice versa, to lock said frame 2 in one or another predetermined position to which it has been adjusted transversely of the machine. Said 95 lever may be secured in operative position by a spring 7 fixed at one end to the frame 1 and engaging a groove in the end of the lever 6. The tendency of the free end of the spring 7 when under tension by engage- 100

110

ment with the lever 6 is, in the form illustrated, to move downwardly, thus forcing that part of said lever, which is on the opposite side of the pivotal axis, upward; and, 5 since the pivotal axis of the lever 6 is eccentric to the dog 6^a, said dog is by the action of the spring and lever moved into engagement with the lug 2^a. Mounted in said frame 2, are journal boxes 8 secured 10 therein against vertical movement by a cover 9 bolted to the frame 2 and against longitudinal movement by pins as 9^a (Fig. 1) directed through the cover 9 and into the top of the box or boxes. Journaled in 15 said boxes is a shaft 10 extending transversely of the machine, to which is keyed one or more gear wheels 10^a and one or more belt wheels 10^b. Secured to, or formed on said frame 2, are guide blocks 11, and 11^a 20 spaced apart, and, supported thereby, are bars 12 and 13, parallel with said shaft 10. The bars 12 and 13 are apertured to receive a spindle or spindle 14, extending therethrough and provided with pinions 14^a 25 meshing with corresponding ones of said gears 10^a. Said spindles are prevented from vertical movement, in said bars, by any suitable means or in any suitable manner, as preferably by collars 14^b, 14^c bearing upon 30 or against one of said bars, which collar 14^c may be integral with the pinions 14^a. Mounted on said frame 2, between said guide blocks, is a pressure yoke or yoke-shaped pressure foot 15, which is apertured to receive the drills 16 which drills are secured in any suitable manner in said spindles. The central portion of said yoke extends transversely of said machine and the vertical arms extend up between the respectively contiguous guide blocks, but not to 40 the upper end of the guide blocks.

The upper end of the yoke are recessed to receive a spring 15^a (Fig. 2) and a plunger 15^b, which plunger bears upon the spring 45 and against the end of the bar 12 which bar is preferably bolted to the upper ends of the guide blocks. Thus the yoke may yield upwardly against the springs 15^a which, however, tend to hold said yoke down upon the article to be drilled, hereinafter described. In order to prevent said plunger from jumping out of the recess in the yoke, the barrel of the plunger is reduced intermediate of its ends, and a pin or screw 15^c (Fig. 3) is 55 projected through the wall of the yoke and into the space formed by the reduction in the barrel of the plunger. In order to prevent the yoke from dropping out of the frame 2, when said frame is tilted back, said 60 yoke is recessed in the outer face of its side wall, and a screw or pin 15^a is projected through the adjoining guide block into said recess. Said yoke is also transversely slotted or grooved as at 15^e in its lower face at the 65 points of passage of each drill to afford pas-

sages for the escape of filings or shavings cut by the drills from the articles to be drilled. Mounted or formed on a cross bar 1^f of said frame 1, is a journal bearing 1^g 70 in which is journaled the axle 17 of a worm wheel 18, which is provided with a hub 19, said hub 19 has a cam, or inclined plane formed upon its free end upon which rests a vertically reciprocating yoke or support 75 provided at its center with a hub 20^a having a cam face or inclined plane upon its lower end contacting with the inclined plane formed upon the hub 19. Journaled in said yoke 20, is a shaft 21, carrying a sprocket wheel 22 keyed thereto, and a sprocket wheel 22^a loose on the shaft and bolted to a disk 22^b which is keyed to said shaft, the bolts passing through slots in the sprocket wheel or else in the disk, so that the sprocket wheel can be adjusted properly with relation to 80 the wheel 22 and there fixed in such relative position by tightening the bolts which secure it to said disk. The shaft 21 extends at each end through sliding journal boxes 20^b movable vertically in guides 20^c formed on or 85 secured to said frame 1, said shaft also extends through slots 1^h formed in said frame 1, and each end of said shaft is preferably provided with a retaining collar 20^d. There is also mounted on said shaft near one end 90 thereof a gear or cog-wheel 23, keyed thereto. Said shaft is adapted to be rotated by means of a lever 24 journaled upon the shaft and provided with a spring bolt 24^a adapted to engage one or another of a series of recesses or apertures 23^a in the hub of said gear 23. A guard is preferably provided for said gear 23 and preferably comprises a disk 25 provided with a flange 25^a, and with a hub 25^b mounted on and keyed to a hub 95 projecting from the adjoining sliding journal bearing 20^b. Said flange 25^a is slotted or partly cut away to permit the passage of the nose of a dog 26, which dog is hinged upon a shoulder or rib formed on said disk 25 and is adapted to dip through said slot and engage the teeth of said gear to prevent the rotation of said gear and of the shaft upon which said gear is mounted. When it 100 is desired to rotate said shaft 21 the dog 26 is, preferably by manual operation, disengaged from the teeth of said gear; the handle of the lever 24 is then grasped, and the gear and shaft is rotated as far as desired by means of said lever. 105

The upper end of the yoke 20 has formed thereon, or secured thereto a cross bar 20^e and a superimposed bar 20^f in the upper face of which bar 20^f transversely of the same, are formed one or more recesses or grooves to 110 receive the lower ends of the drills after they have passed through the article to be drilled. The number of said recesses will correspond to the number of holes to be drilled in one line transversely of the ma- 115 120 125 130

chine and they are so spaced that a recess will register with each drill in whatsoever drilling position said frame 2 may be locked by the dog 6^a. Said grooves are also adapted to operate as passages for the escape of filings or shavings cut by the drills from the article to be drilled. It is obvious that without departing from the spirit and scope of my said invention, said recesses may extend through said bar vertically instead of being formed as transverse grooves in the upper face thereof. Pivotal secured to the upper end of said yoke are oppositely directed tables 27 and 28 respectively, which at their opposite ends are pivotally supported upon legs, as at 27^a, and at 28^a, respectively. The articles to be drilled are preferably moved upon the table 27 toward the yoke 20 and away from it upon the table 28. Journaled in suitable bearings upon said frame 1 is a shaft 29 upon which is formed or secured a worm 30, adapted to engage the gear 18. A suitable belt wheel or wheels 31 are keyed to said shaft 29 to turn the same. A suitable belt wheel 10^b is also keyed to the shaft 10, which is belted in operation to a belt wheel on the shaft 29 which shaft 29 is driven through a belt wheel 30^a in any suitable manner by any suitable form of motor not shown; but any suitable arrangement of gears, not shown, or other equivalent, may be substituted for the belt wheels.

I will now describe the operation of my invention when employed in drilling splint-receiving holes, in a match carrying belt. The belt is first formed by uniting the slats 33 to the links 34 and engaging the links together. The belt is then stretched along the table 27, and if desired, or of great length, part of the belt, toward the rear end of said table may be rolled and it may be gradually unrolled as it is fed to the drills. The forward end of the belt to be drilled is then passed between the bar 20^c and the central part of the yoke 15, and at the same time the links of said end of said belt are dropped upon the teeth of the sprocket wheels 22, and 22^a. During this preparatory operation, the frame 2, may be tilted upward and backward upon the shaft as at 2^b (Fig. 9), and may be restrained from tilting too far by a stop link 35, of well known construction. If not already lowered, the frame 2 is then lowered so that the drills bear upon or come near to the surface of the first slat to be drilled. The frame 2 is preferably at first locked at one end of its path of transverse travel, and the yoke 20 is at its lowest position. The power belts are then connected and the machine is started. The worm now turns the gear 18, and the cam on the hub 19 operating against the cam 20^a raises the yoke which carries up the slat against the rapidly revolving drills until they penetrate the same. The shaft 21 of

course rises with the yoke 20 and carries up the various members mounted thereon. When the gear 18 has made nearly one revolution, the high point of each cam drops onto the low point of the respectively opposite cam and the yoke thereupon drops away from the drills. The dog 6^a is then disengaged and the lever 5 is then operated to thrust or draw the frame 2 in the desired direction and for the desired distance and the dog 6^a is again engaged and the operation is continued to bore a second series of holes in the same slat and in alignment with the first series of holes.

It should be remarked that the construction of the cams on the hub 19 and the cam 20^a is preferably such that the inclined planes only occupy a portion of the circumference of the hubs and that therefore the gear will turn some distance before the yoke 20 or vertically movable support 20, commences to rise. This affords time for shifting the frame 2; otherwise, the belts connecting the machine with the motor could be disengaged to afford time for such shifting. After boring the second series of holes, the frame 2 may be again shifted and a third series of holes bored in the same slat in alignment with the other holes therein. The machine may be constructed, if desired, to bore additional series of holes in the same manner. After all the holes are bored that are desired in one slat, the dog 26 is disengaged and the lever 24 is operated to partly rotate said shaft so as to bring another slat in position for being drilled. The dog 26 is then reengaged and the operations of drilling the second slat are gone through with; and so on, until the entire splint carrying belt has been drilled.

Since it may sometimes be desirable to arbitrarily raise the yoke 20, independently of the usual motive means, I provide the lever 36 (Fig. 9) which extends under the lower end of the axle 17 depending from the yoke 20 loosely through the center of the gear 18 and forming the axle of the gear 18. Said lever is adapted to bear against said post and so raise said yoke 20.

What I claim as my invention is,

1. The combination of a main frame, a support mounted in said frame, a transversely adjustable head frame hinged on said main frame and adapted to swing upwardly, means for locking said head frame in one or another of the positions to which it may be adjusted transversely of the machine, drill carriers mounted on said head frame, means mounted on said head frame for driving the drills, and a yielding pressure yoke carried by said head frame and adapted to bear upon the article to be drilled.

2. The combination of a frame, a support mounted thereon, a transversely movable drill-carrying means mounted on said frame,

means for laterally positioning said carrying means, a yielding presser foot mounted on said drill-carrying means and having passages formed therein for the drills, means 5 for exerting pressure on said foot to press the same on the article or articles to be drilled, means for rotating said drills, and means adapted to feed across said support beneath said presser foot the article or articles 10 to be drilled.

3. In a drilling machine, the combination of a frame, a vertically movable support mounted on or in said frame, means for raising said support, a shaft journaled in said support, propelling means governed by said shaft, slides loosely mounted on said shaft, guides for governing the direction of movement of said slides, a cogged wheel keyed to said shaft for rotating the same, a lever 15 for actuating said wheel, a guard for said wheel and concentric therewith keyed to a shoulder or hub formed on one of said slides, and a dog pivoted on said guard, and adapted to engage one or another of the 20 teeth of said wheel, to prevent the rotation of the same.

4. In a drilling machine, the combination of a frame, a vertically movable support mounted on or in said frame, tables or guides 30 approaching said support in opposite directions and at an angle to the direction of travel of said support and pivotally connected at their opposing ends to said support near its upper end.

35 5. In a drilling machine, the combination of a main frame, a head frame hinged thereon and adapted to swing upwardly, slides mounted on the main frame and adapted in operation to overlap a portion of the head 40 frame to hold the same in its lowered position.

6. In a drilling machine, the combination of a main frame, a head frame hinged thereon and adapted to swing upwardly and also 45 adapted to move transversely of the machine parallel to the axis of its hinge, a lever fulcrumed on said main frame, a link connecting said lever to said head frame, whereby said head frame may be moved transversely 50 of said machine, a lever pivoted to said main frame and carrying teeth adapted to engage teeth formed on said head frame for

locking said head frame against transverse movement.

7. In a drilling machine, the combination 55 of a head frame having guides secured or formed thereon, a drill carrying bar mounted on said frame, a pressure yoke apertured for the passage of the drills and mounted between said guides, said yoke being recessed in its upper ends and grooved in its lower face from each drill passage forwardly, a spring in each of said recesses, a plunger in each of said recesses above the springs and adapted to bear at one end 60 against a fixed abutment, and at the opposite end against said spring to depress said yoke, and a pin or screw extending through one of the adjoining guides and into an elongated recess in the adjoining arm of the 70 yoke to limit the movement of said yoke.

8. In a drilling machine for drilling match-holding holes in the slats of a match carrying belt, the combination of a main frame, a vertically movable support mounted thereon, approaches pivoted to said support for conveying the belt to be operated on, sprocket wheels mounted on said support and adapted to engage the links of the belt to be operated on and to effect an intermittent 80 movement of said belt along said approaches, means for raising said support intermittently, means for actuating said sprocket wheels, a head frame mounted on said main frame and adapted to be moved in 85 a transverse direction, means for moving said head frame transversely of the line of travel of the belt to be drilled, means for locking said head frame in a predetermined position, a series of drills carried by said 90 head frame and adapted to bore into the slats of said belt when the same are carried up against the drills by the said vertically movable support, a spring controlled pressure yoke adapted to press upon the slat beneath the drills so as to hold the same flat upon its support and so as to prevent play of 95 said slat, and means for rotating said drills.

In testimony whereof I hereunto affix my signature, in presence of two witnesses.

JOHN W. LUNDGREN.
